UNITED STATES PATENT OFFICE.

FRANK B. FRETTER, OF CLEVELAND, OHIO, ASSIGNOR TO THE NATIONAL REFINING COMPANY, OF CLEVELAND, OHIO, A CORPORATION OF OHIO.

METHOD OF AND MEANS FOR TREATING FLUID HYDROCARBONS.

Application filed June 18, 1925. Serial No. 37,941.

My invention relates to improvements in method of and means for treating fluid hydrocarbons, and has primarily for its object the economical treating of such hydrocarbons to insure the rearrangement of molecules and produce what commonly is termed in the art as "cracking" for obtaining a gasoline content.

The procedure differs from any with which I have previously become acquainted by reason of the fact that the fluid hydro-carbon is maintained under an excessive pressure during the heating thereof, which pressure preferably is produced by a high pressure pump, acting against a small orifice, while the treated hydrocarbon is suddenly released from such pressure through an accelerating vent, such as a Venturi tube or outlet, whereby the cracking operation is materially augmented.

As a secondary object of my invention, I effect a recycling of the treated stock and conservation of heat, so that a maximum cracking effect is obtained with attendant economies.

The process and apparatus suitable for practicing the same may best be explained in connection with the accompanying drawings, wherein:

Figure 1 is a diagrammatic view, principally in vertical sections, illustrating means for practicing the process or method of my invention.

Figure 2 is an enlarged view, in vertical section, of the adjustable discharge nozzle associated with the apparatus diagrammatically shown in Figure 1, and

Figure 3 is an end view of the said nozzle.

Throughout the several figures of the drawings, I have employed the same characters of reference to indicate similar parts.

Referring first to the diagram of Figure 1, there is shown, at the left of the drawing, a tube heater, *a*, having a gas burner, *b*, and a chimney stack, *c*′, all of the usual type. The terminal connectors, *c*′, of the tubes, *c*, preferably maintain throughout the heater an equal area for the free passage of the fluid hydrocarbons.

This heater, *a*, is supplied by a high pressure pump, *d*, to wit, one that will be capable of maintaining a pressure upward of one thousand pounds (1,000#) per square inch, and the system of connected tubes obviously is adapted to withstand pressures considerably in excess of this figure.

Leading to the right from said pump, *d*, is a pipe, *e*, which connects with the tower, *f*, internally provided with baffling, *f*′, and a supply pipe, *g*, extends to the base of the tower and is connected with a supply of suitable fluid hydro-carbon, such as gas oil or kerosene distillate, for example, although it will be understood that my process is not dependant upon any particular gravity of hydro-carbon.

Assuming that the tower, *f*, has been filled approximately one-eighth (1/8) of its height, as indicated, this level will be maintained and against the supply in said tower, the pump, *d*, will be started, filling the tubes of the heater with fluid hydro-carbon. The burner, *b*, is then ignited, and the needle valve, *h*′, of the nozzle, *h*, is slightly opened to permit the continued flow of hydro-carbons while heating, and prevent the burning out of the tubes. Roughly, the pressure maintained by the pump, *d*, will increase proportionately with the temperature as observed upon the thermometer, *i*; one hundred and twenty-five pounds (125#), approximately, being maintained at 100 degrees F.; five hundred pounds (500#) approximately, being maintained at 400 degrees F.; eight hundred and seventy-five pounds (875#), approximately, being maintained at 700 degrees F., and one thousand pounds (1,000#) and upward being 75 maintained at eight hundred (800) degrees F. and upward, these figures being applicable to gas oil or kerosene distillates but, obviously, would vary with other hydrocarbons, 80 under treatment.

It is obvious that, in order to attain any considerable pressure upon the tubes, some back pressure device is essential, which may be embodied in a restricted orifice of any suitable character. In order to regulate the size of the orifice in accordance with different working conditions and different distillates, I preferably employ the nozzle, *h*, which is shown in Figures 2 and 3, although my invention does not necessarily depend upon the mechanical details therein shown, and which I will here describe.

This nozzle, *h*, embodies the features of a velocity tube, comprising a gradually constricted neck, *h*′, connecting with the needle valve seat, *h*‡; the needle valve stem, *h*§, loosely sliding in a spider, *h*¶, and controlled at the opposite or left hand end by a screw, *h*§, and hand wheel, *h*¶, while a gland, *h*¶, is packed to resist the high pressures necessarily 105 110 115

placed upon this appliance. It will be observed with this construction, the valve stem being of even diameter upon the entering side of the velocity tube, that an even flow may be accurately figured and maintained with a given opening of the needle valve, h' . Under working conditions, the opening will approximate three-eighths ($\frac{3}{8}$) of an inch area, using gas oil as the treated hydro-carbon.

10 Against the needle valve, h' , the pressure will gradually be built up, as previously stated. Thus the hydro-carbon is injected at a materially accelerated rate into the vaporizer, j , at an excessive temperature 15 ranging above 800 degrees F., and a pressure approximating one thousand pounds (1,000#) and upward, which pressure is instantly released in a vaporizer and dome, j' , that are open to the tower, f , and thus the 20 heated hydro-carbon is suddenly released practically at atmospheric pressure.

A pipe of large diameter, j'' , leads into the tower, f , beneath the baffling, f' , and the vaporous hydro-carbon will immediately 25 seek exit through the tower, f , and baffling, f' ; the heavier fractions thereof condensing at approximately 350 to 400 degrees F., and seeking the bottom of the tower, f , while those still in vaporous condition would pass over 30 through pipe, f'' , to the cooling box, k . This distillate, which is condensed in k , comprises the crude benzine and may be treated in the usual manner for obtaining its gasoline content.

35 Turning now to a more detailed discussion of my process, and my understanding of the theory under which it operates, I may say that the treated hydro-carbon is maintained in fluid condition, by reason of the excessive 40 pressure maintained by pump, d , and is driven so rapidly through the tubes, c , of the heater, a , that no material deposit is left within the tubes, and no actual cracking takes place, until the hydro-carbon is instantaneously freed from said pressure by being 45 driven through the adjusted orifice of the nozzle, h .

At least, an immediate separation occurs 50 between the vaporous hydro-carbons as introduced into the vaporizer, j ; the heavier constituents remaining in fluid condition and being drawn off from time to time through the valve, j''' , while the gaseous hydro-carbons which have been partly cracked at this 55 stage will flow through the tower, f , and be separated by the usual condensing action therein, as previously indicated.

It is obvious that the supply within the base of the tower, f , soon becomes heated by 60 the condensing hydro-carbons from the baffling, f' , and from this heated supply, augmented by the newly supplied hydro-carbons, the pump, d , recycles the hydro-carbon for further treatment in the tubes, as 65 previously explained.

A discharge valve, l , is provided in the line leading from the heater, a , if it is necessary, for any reason, to suspend the cracking operation within the vaporizer, j ; the needle valve h' then being tightly closed.

Another discharge valve, m , is provided for draining the accumulated hydro-carbons from the base of the tower, f , in case of shutdown or repairs.

A high pressure gauge, n , is provided adjacent to the pump, d , and a vacuum and atmospheric pressure gauge, o , is provided upon the dome of the vaporizer, j ; while liquid gauges, p and q , respectively, are associated with the vaporizer, j , and the tower, f , but these and other details do not require description nor further illustration in explaining my invention to those skilled in the art.

One other detail, however, may be adverted to, comprising the discharge valve, r , associated with the tubes of the heater. When it is necessary to discontinue operations, the valve, r' , connected with a high-pressure steam line, is opened concurrently with the stoppage of pump, d , and the valve, l , also is 90 opened. This permits the cooling of tubes and their substantial discharge, after which the draw-off valve, r , is opened to drain the remnant of oil and water therefrom.

Apparently the hydrocarbon within the 95 heater tubes is in an imminent state of dissociation but is maintained in initial fluid form by the excessive pressure applied thereto by the pump. The velocity tube may conform to the lines of, or approximate a Venturi tube, in order that the discharge may be more rapid and effective within the vaporizer. As recycling proceeds, or a hydrocarbon of higher specific gravity is employed, the temperature may be advantageously increased, 100 say to 850° F., and upward, while the pressure will be regulated from time to time in correspondence with the instant working conditions, of which I have given an illustrative example above. In all cases, extreme 105 care must be exercised to prevent the burning out of the pressure tubes within the heater.

It will be seen that the separation of the heavier hydrocarbons is effected in this process immediately upon the discharge of the treated hydrocarbon into the vaporizer under normal pressure, i. e., slightly above or below atmospheric pressure. This separation is preferable so as to avoid recycling those hydrocarbons which are substantially 110 resistant to cracking operations.

In considering the appended claims, the acceleration referred to therein at the moment of the discharge of the hydrocarbons, and the velocity tube for obtaining such acceleration and increase in the cracking reaction, relate to the known action of the Venturi tube and its physical features, respectively, and the claims are to be read with this definition in mind.

Having now described the method of my instant improvement, and indicated apparatus suitable for the practice thereof, I claim as new and desire to secure by Letters Patent, 5 together with such modifications as may be made by those ordinarily skilled in the art, the following:

1. The herein described method of treating fluid hydrocarbons, which consists of 10 rapidly impelling the treated hydrocarbon through a heater under extraneous pressure approximating 1000 pounds per square inch and obtaining a working temperature for said hydrocarbon in excess of 800° F., permitting the escape from the heater of graduated 15 volumes of the hydrocarbon through an accelerating vent having the characteristics of the Venturi tube into a vaporizing chamber at approximately atmospheric pressure, and 20 separating the heavier and lighter hydrocarbons resulting from this treatment, substantially as set forth.

2. The herein described method of treating fluid hydrocarbons, which consists of pumping 25 the treated hydrocarbon through a tube heater under pressure in excess of 1000 pounds per square inch and a temperature upward of 850° F., at a rate to prevent material deposit within the heater, unrestricted 30 by accelerating the escape of the hydrocarbon from the heater into a vaporizing chamber, substantially at atmospheric pressure as by Venturi tube action, whereby the released hydrocarbon is subjected to a cracking 35 action and effecting the separation of the heavier and lighter hydrocarbons resulting from said treatment, substantially as set forth.

3. The herein described method of treating 40 fluid hydrocarbons, which consists of rapidly impelling the treated hydrocarbon through a heater of restricted cross-sectional area under extraneous working pressure approximating 1000 pounds per square inch and at a mesne working temperature of 800° F., more 45 or less, unrestrictedly accelerating the escape from the heater of graduated volumes of the hydrocarbon into a vaporizing chamber at nominal pressure as by Venturi tube action, and 50 separating the heavier and lighter hydrocarbons resulting from this treatment, substantially as set forth.

4. The herein described method of treating 55 fluid hydrocarbons, which consists of rapidly impelling the treated hydrocarbon through a heater of restricted cross-sectional area under extraneous working pressure approximating 1000 pounds per square inch and at a

mesne working temperature of 850° F., more or less, unrestrictedly accelerating the escape 60 from the heater of graduated volumes of the hydrocarbon into a vaporizing chamber at nominal pressure as by Venturi tube action, separating the heavier and lighter hydrocarbons resulting from this treatment, and 65 recycling the distillate condensing at 400° F., more or less, substantially as set forth.

5. In apparatus of the class described, a combined elbow and velocity tube for cracking 70 chambers, comprising an elbow member tapered past the turn thereof to form a Venturi-tube outlet, a valve member in the axis of said tube, a packing at the elbow, and screw-acting means for opening and closing the outlet, substantially as set forth. 75

6. In apparatus of the class described, comprising a combined elbow and velocity tube for vaporizing chambers and the like, an elbow member having a relatively large inlet at an angle with a tapered section forming 80 a Venturi-tube outlet, a movable reversely tapered valve rod positioned in the axis of said tube, a packing at the elbow turn, and exterior screw-acting means for opening and closing the outlet and for regulating its opening or clearance, substantially as set forth. 85

7. The herein described method of treating fluid hydrocarbons which consists of rapidly impelling the treated hydrocarbon through a constricted heater under extraneous pressure 90 approximating 1000 pounds per square inch and obtaining a working temperature for said hydrocarbons in excess of 800° F., effecting the accelerated escape from the heater of graduated volumes of the hydrocarbon, as by 95 Venturi action, into a vaporizing chamber approximately at atmospheric pressure, and separating the heavier and lighter hydrocarbons resulting from said treatment. 100

8. The herein described method of treating fluid hydrocarbons, which consists of rapidly pumping the treated hydrocarbons through a heater of restricted cross sectional area and extended length under extraneous working pressure approximating 1000 pounds per square inch and at an approximate working temperature of 850° F., more or less, effecting the accelerated escape, as by Venturi action, of graduated volumes of the hydrocarbons 105 into a vaporizing chamber at nominal pressure, and separating the heavier and lighter hydrocarbons resulting from said treatment and accelerated discharge. 110

In testimony whereof I do now affix my signature.

FRANK B. FRETTER.
